United States Patent Office

Des. 223,977

Patented June 20, 1972

223,977

COMBINED DOLL AND MIRROR

Perry Feuer, Roslyn, N.Y., assignor to Creative Creations, Inc., New York, N.Y.

Filed Jan. 8, 1971, Ser. No. 105,146

Term of patent 14 years

Int. Cl. D28—03

U.S. Cl. D86—10

FIG. 1 is a front elevational view of a combined doll and mirror showing my new design;

FIG. 2 is a rear view of the design;

FIG. 3 is a left perspective view of the design; and

FIG. 4 is a right perspective view of the design.

I claim:

The ornamental design for a combined doll and mirror, as shown.
